CONTAINER

Maximilian Paul Link, Los Angeles, Calif.

Application November 8, 1935, Serial No. 48,846

7 Claims. (Cl. 229—5.7)

This invention relates to a container and relates more particularly to a sealed container formed of paper, fiber, cardboard stock or the like, or combinations of such materials. A general object of this invention is to provide an improved, particularly effective and inexpensive container.

Another object of this invention is to provide a container formed of paper, fiber, cardboard stock or the like, or combinations of such materials, that is strong and dependable being adapted to contain various forms and classes of substances in a manner to prevent the leakage, spoiling and contamination of its contents.

Another object of this invention is to provide a container of the character mentioned in which the ends, that is, the top and the bottom, are secured to and sealed with the container body by improved, strong and particularly simple securing and sealing means.

Another object of this invention is to provide a container of the character mentioned in which the heads or ends may be identical and the means for connecting both ends in sealing and closing relation with the container body and the manner of securing both ends to the container body may be identical thus facilitating the assembling of the container and greatly promoting economy in its manufacture.

Another object of this invention is to provide a container of the character mentioned that is sturdy and strong being capable of dependably withstanding the hard usage to which tin cans and other containers are subjected.

Another object of this invention is to provide an improved container of the character mentioned in which the heads or ends are so securely attached to the body of the container in sealed relation thereto that they will break under severe pressures before pulling free from the body and before leaks will develop at the lines of connection between the ends and the container body. The means for securing the ends to the container body of the container of this invention are such that the ends and the adjacent wall parts of the body may be bent and distorted to a considerable extent before leaks develop and before the ends become loosened from the body.

Another object of this invention is to provide a container of the character mentioned in which one or both ends may be loosely or partially attached to the container body when the container is in condition for delivery to the user or packager in which case the end or ends may be removed to permit filling of the container and then quickly secured to and sealed with the container body immediately following the sealing of the container.

Another object of this invention is to provide a container of the character mentioned in which one end or both ends may be easily and quickly

removed from the container body by means of a proper instrument without injury to the person opening the container and without leaving sharp edges on the container but cannot be tampered with or pried open without leaving very visible 5 and apparent indications of such tampering or prying.

Another object of this invention is to provide an improved container of the character mentioned in which an end may be easily removed 10 from the body in its entirety to permit the removal of a portion of the contents of the container and then may be replaced to form a cover which prevents the entrance of foreign matter to the container and, if desired, may be replaced 15 on the container body in a manner to prevent spilling of the remaining contents.

Another object of this invention is to provide a container of the character mentioned in which one or both of the ends may be tightly or rather 20 loosely secured to the container body depending upon the character of the contents to in either case seal the container against leakage and to fully protect the contents. If the end or ends are loosely applied to the container body it or they 25 may be easily removed therefrom without using an opening instrument.

Another object of this invention is to provide a container of the character mentioned that is 30 light in weight and attractive in appearance, the rings securing the ends in sealed relation to the container body being small and compact and of attractive design.

A further object of this invention is to provide a container of the character mentioned in which the means for attaching an end to the container body and for providing a tight seal between the end and body comprises a single ring of metal or other suitable material which tightly clamps a flange of the end against the internal surface of the body, securely grips the edge portion of a rim on said flange at the outer surface of the body and tightly grips the wall of the container body at its outer surface, thus insuring a firm, strong, mechanical connection between 40 the end and body and providing a leak-tight seal between the end and body without being in contact with the contents of the container.

The various objects and features of my invention will be fully understood from the following 50 detailed description of a typical preferred form and application of my invention, throughout which description reference is made to the accompanying drawing, in which:

Fig. 1 is a perspective view of a container 55 embodying the present invention. Fig. 2 is an enlarged fragmentary longitudinal detailed sectional view of the container. Fig. 3 is an enlarged fragmentary longitudinal detailed sectional view showing a head positioned for ar- 60

angement on the container body. Fig. 4 is a view similar to Fig. 3 with the head arranged on the body. Fig. 5 is a view similar to Fig. 3 showing the head finally secured to the container body and Fig. 6 is an enlarged view similar to Fig. 5 illustrating a slightly modified form of the invention.

The present invention is adapted to be embodied in containers of various shapes and sizes 10 and in containers intended to contain various substances. Further, the invention contemplates the formation of the container of various materials and combinations of materials. Throughout the following detailed disclosure I will describe a single typical illustrative embodiment of the invention, it being understood that such disclosure is not to be construed as limiting or restricting the scope or range of the invention.

The improved container of the present invention illustrated in the drawing includes, generally, 20 a container body 10, ends or closure heads 11 for closing the opposite ends of the body 10, and means 12 securing the heads 11 to the container body 10 and providing air tight and leak tight 25 seals between the heads 11 and the body.

The body 10 of the container is preferably tubular and in practice may constitute a length or portion of suitable tubular stock. The invention contemplates the formation of the container body 30 10 of paper, pressed paper, fiber or similar materials or combinations of such materials. The body 10 of my improved container may comprise a spirally wound strip of material of the general class mentioned or strips of such material which 35 may be doubly wound or spiralled in opposite directions or the body may be formed in any other manner. In the typical form of the invention illustrated the body 10 is cylindrical, it being understood that the body may be cone shaped 40 or may be polygonal or oval in transverse cross section. The ends 13 of the tubular container body 10 are preferably flat and preferably, though not necessarily, lie in planes at right angles to the longitudinal axis of the body. It is to be 45 understood that the body 10 may be treated or coated either internally or externally or both, to be moisture proof and impenetrable by the contents which it is intended to hold. The tubular container body 10 may be furnished to the user or packager with either one or both of the closure 50 heads 11 loosely or partially secured thereto by the means 12. When the container body 10 is cone shaped a multiplicity of such bodies 10 may be supplied to the user or packager nested one 55 within the other and each body 10 thus nested may have a head 11 secured to or partially secured to its small end.

The ends or closure heads 11 are provided to 60 close the opposite ends of the tubular container body 10. In practice the heads 11 may be formed of paper, pressed paper, board, fiber or similar material provided with linings of paper or treated paper on either their external or internal surfaces, or both. It is an important feature of the 65 invention that the two heads 11 of the container may be identical in shape and construction and where the body 10 is cylindrical or of the same shape and dimensions at its opposite ends the two heads 11 may be identical. Fig. 6 illustrates 70 a head 11* provided with an outer covering 30 in the form of paper adapted to carry printed matter or the like and provided with a lining 31 of paper or the like on its inner surface which may be treated as required. The coverings 30 75 and the lining 31 may cover the entire inner and

outer surfaces of the head 11* to have their peripheral portions engaged by the securing means 12 to be subsequently described.

The closure heads 11 are substantially disc shaped in their general configuration and their major portions are flat. If desired or necessary one or more circular corrugations 14 may be provided in the heads 11 to render them more rigid. The peripheral portions of the heads 11 are shaped for engagement with the body 10. In accordance with the invention an axially projecting flange 15 is provided on each head 11. The flanges 15 are continuous and in the case illustrated where the body 10 is cylindrical the flanges 15 are annular. The flanges 15 are intended to fit within the end portions of the body 10 and to bear outwardly against the internal surface of the body. It is preferred to make the flanges 15 outwardly flaring to tightly fit or engage in the end portions of the tubular body 10. Fig. 3 of the drawing illustrates a flange 15 of a head 11 entering the tubular body 10 and illustrates the wedging cooperation of the flaring flange 15 with the internal surface of the body 10. As the heads 11 are initially formed they are 25 provided with rims 16 projecting radially outwardly from the outer ends of the axial flanges 15 to be substantially parallel with the planes of the bodies of the heads 11. The rims 16 are continuous or annular and are integral parts of 30 the heads 11. In this regard it is to be noted that the closure heads 11 of the container are simple inexpensive parts. In the particular case illustrated in the drawing the closure heads 11 are both imperforate, it being understood that 35 one or both heads 11 may have discharge openings or perforations for facilitating the removal or discharge of the contents from the container.

The means 12 for securing the heads 11 to the body 10 and for providing fluid tight and leak tight seals between the heads 11 and the body 10 is an important feature of the invention. As the two heads 11 may be identical the means 12 for securing the heads 11 in sealing relation to the body 10 may be identical. This is important as it greatly facilitates the manufacture and assembling of the container and thus provides for general economy. As the means 12 for securing the two heads 11 to the container body 10 may be identical I will proceed with a detailed description of the means 12 for securing one head 11 with the body 10, it being understood that such description may apply equally well to the means for securing the other head 11 to the body 10.

The means 12 for securing the head 11 to the container body 10 comprises an attaching or securing ring 18. As initially formed the ring 18 is substantially L-shaped in transverse cross section having a flange 19 extending in the direction of its axis and a radially outwardly projecting flange 20. The ring 18 may be a simple integral member. The invention contemplates the formation of the ring 18 of metal or certain other materials such as suitable plastics that are capable of deformation or shaping when subjected to heat. In the simple embodiment of the invention illustrated in the drawing the ring 18 is relatively light and has smooth surfaces. The axial flange 19 of the ring 18 is adapted to bear 70 against the inner surface of the head flange 15. Accordingly, the flange 19 is preferably slightly tapered or outwardly flared to properly seat in the flange 15. The ring 18 is suitably curved or rounded where the flanges 19 and 20 join. The 75

radial flange 20 is adapted to cooperate with the rim 16 of the head 11 and with the wall of the body 10 as will be hereinafter described.

The rim 16 of the head 11 and the radial flange 20 of the ring 18 are adapted to be shaped or rolled to be locked together and to be brought into gripping and sealing cooperation one with the other and with the wall of the body 10. It may be preferred to roll the rim 16 and the flange 20 into locked or holding cooperation before applying the head 11 to the container body 10 so that the head 11 and the ring 12 may be supplied to the user as a unit for quick application to the body 10. The radial flange 20 of the ring 18 as initially formed projects some distance outwardly beyond the periphery of the rim 16. The projecting peripheral edge portion of the flange 20 is curled or rolled around the peripheral edge of the rim 16 to have a part 21 which engages the under or inner surface of the rim 16 and the engaging rim 16 and flange 20 are rolled or curved to project in the general direction of the axis of the ring and head 11. The shape of the head 11 and the ring 12 following this initial rolling operation is illustrated in Fig. 3 of the drawing. It will be noted that the inner portions of the rim 16 and the flange 20 remain substantially normal to the axis of the ring 18 and substantially parallel with the body 10 of the head 11 and that the rolled in portion of the rim 16 and the engaging portion 22 of the ring flange 20 taper or are inclined outwardly.

The rolled in peripheral edge portion of the flange 20 forms the locking or gripping part 21 which tightly engages and seals with the rim 16 and tightly grips the peripheral edge portion of the rim 16 to securely connect the ring 18 with the head 11. It will be observed that the outer curved portion 22 of the flange 20 and the part 21 receive the curved peripheral edge portion of the rim 16 to provide a strong positive connection between the ring 18 and the head 11. The part 21 and the curved peripheral portion of the rim 16 are spaced outwardly from the flange 16 leaving an annular groove 23 which is adapted to receive the end portion of the body 10 as will be subsequently described. It will be apparent that curling or rolling of the ring flange 20 onto the rim 16 brings the flange 19 into tight contact with the head flange 15 and brings the portion 22 of the flange 20 in tight sealing contact with the outer surface of the rim 16. The inner end of the ring flange 19 may engage the outer surface of the head 11 to strengthen the assembly. The shaping or rolling of the ring 18 as described above may be accomplished by a suitable curling tool. The head 11 and the ring 18 secured together by the rolled together rim 16 and the ring flange 20 form a simple unit that may be supplied to the user or purchaser for application to the container body 10 or the head 11 and the ring 18 may be supplied separately to be assembled when the container is sealed.

The closure head 11 with the rolled on ring 18 is adapted to be arranged on the end portion of the container body 10. When the assembly of the head 11 and the ring 18 is arranged on the body 10 the head flange 15 enters the end of the tubular body 10 and bears against its inner surface while the straight or unbent portion of the rim 16 seats on the end 13 of the body 10. The space or groove 23 receives the end portion of the body 10. The taper of the flange 15 provides for the effective wedging of the flange against the internal surface of the body 10. With the

head 11 in the position where the straight portion of the rim 16 engages the end of the body 10 the part 21 and the curved portion of the rim 16 are at the outer surface or side of the body 10. Fig. 4 of the drawing illustrates the relationship between the parts just described.

Following the arrangement of the closure head 11 and the connecting ring 18 on the body 10 the part 22 of the ring flange 20 and the rim 16 are curled or rolled inwardly to secure the head 11 to the body and to provide a dependable seal between the body and head. In practice the flange part 22 and the rim 16 may be rolled in to finally or permanently seal the head 11 to the body 10 or they may be only partially rolled inwardly to bear rather lightly against the wall of the body 10 so that the head 11 may be removed without the use of an opening instrument. For the purpose of example it will be assumed that the head 11 is tightly or permanently secured to the body 10 in which case the part 22 of the ring flange 20 is rolled inwardly to bring the part 21 into tight gripping cooperation with the body 10. This engagement or cooperation occurs at a point spaced below the end 13 of the body and the part 21 may be forced inwardly to the extent that it is recessed or partially embedded in the wall of the body 10 to have dependable locking cooperation with the body. Fig. 5 of the drawing illustrates the final position of the parts following the tightening in or rolling in of the part 22 of the flange 20.

The inward curling or rolling of the part 22 of the flange 20 of course results in corresponding inward curling or rolling of the rim 16 and the rim may have bearing and sealing cooperation with the outer surface of the body at the edge of the lock part 21. The peripheral edge portion of the rim 16 is securely gripped between the parts 21 and 22 of the ring flange 20 to positively connect the head 11 with the ring 18 and thus retain the flange 15 and the rim 16 of the head in proper bearing and sealing cooperation with the body. The flange 15 of the head is held in proper bearing and supporting engagement with the adjacent wall portion of the body 10 by the ring flange 19 so that the body wall is reinforced when the ring flange 22 is rolled inwardly insuring the proper embedding of the part 21 in the body wall to provide the lock between the ring 18 and the body 10. The forcing of the part 21 against the wall of the body 10 draws the rim 16 tightly against the outer surface and the end 13 of the body 10 and draws the ring flange 19 tightly against the internal surface of the body wall. The curled under part 21 of the ring 18 tightly clamps against and holds the peripheral part of the rim 16, dependably connecting the head 11 with the ring 18 and the body 10. The crimping or rolling of the securing ring 18 as above described removes or substantially removes the taper from the end portion of the body wall and the flange 15 of the head 11 as illustrated in Fig. 5. The means 12 operating to connect the head 11 with the body 10 in the manner described above provides a dependable seal between the body 10 and the head 11 to prevent the leakage of the contents from the container and to prevent the entrance of air to the container to assure the preservation of the contents.

It is believed that the utility and practicability of the container provided by the present invention will be readily understood from the foregoing detailed description. The container is very light in weight and is very simple and inexpensive of

manufacture because the two heads 11 and the means 12 for securing the two heads to the body 10 may be identical. The means 12 secures the heads 11 to the body 10 to provide a strong mechanical connection between the heads and the body and to positively prevent the leakage of the contents from the body. The gripping engagement of the part 21 with the rim 16 and the wall of the body 10 so securely connects the head 11 with the body 10 that an inward pressure on the head 11 will cause complete failure of the head before the connection between the head and body fails or develops a leak. Further, the means 12 is such that a head 11 and an adjacent portion 15 of the body 10 may be distorted or bent to an appreciable extent before a leak develops. The securing rings 12 are simple attractive parts that do not appreciably increase the bulk or size of the container and do not give the container the appearance of a tin can. A head 11 and its securing ring 12 may be removed from the body 10 as a unit to permit the removal of the contents or a portion of the contents from the container. This removal of the head 11 with its ring 12 may be 20 accomplished with a suitable opening instrument. The head 11 carrying the ring 18 may be replaced on the opened container to form an effective cover for the container. The means 12 is such that a head 11 may be removed in this manner 25 without providing any sharp edges or parts and without excessive disfiguration or mutilation of the container.

Having described only a typical preferred form and application of my invention, I do not wish to be limited or restricted to the specific details 30 herein set forth, but wish to reserve to myself any variations or modifications that may appear to those skilled in the art or fall within the scope of the following claims.

Having described my invention, I claim:

1. In a container, a body, a fibrous head for the body having a flange engaging the inner wall of the body, a rim on the head flange extending over the end of the body and engaging the outer surface of the body, and a metal ring engaging 40 outwardly against the head flange at the inner side of the body wall, engaging inwardly against the rim at the outer side of the body and having a part confined to and wrapped about the edge portion of the rim to grip the same and terminating below the end of the body.

2. In a container, a body, a fibrous head for the body having a flange engaging the inner wall of the body, a rim on the head flange extending 50 over the end of the body and having direct sealing contact with the outer surface of the body, and a metal ring bearing outwardly against the rim to maintain the same in direct sealing contact with the outer surface of the body and having a part wrapped about the edge portion of the rim, said part being spaced below the end of the body and turned outwardly to grip the rim.

3. In a container, a body, a fibrous head for the body having a flange engaging the inner wall of the body, a rim on the head flange extending outwardly over the end of the body to seal against the same and then extending substantially axially of the body at the outer surface of the body 60 to directly seal against the same, a metal ring within the flange of the head, a flange on the ring conforming to and bearing against the rim to urge the rim against the body, and a part on the flange of the ring curled about the edge portion of the rim to grip the same, to be partially embedded in the outer surface of the body and to distort the body to have sealing contact with the head flange and rim and to fully occupy the space between the head flange and rim, the said curled part being spaced from said end of the body.

with the end of the body and the outer surface of the body, and a part on the flange of the ring wrapped about the edge portion of the rim with its inner edge spaced below said end of the body and turned to bite into the inner surface of the rim, said part being curled to clamp inwardly against the outer surface of the body.

4. A container comprising a tubular body, identical fibrous closure heads for the opposite ends of the body, each head including a flange for engaging against the inner surface of the body, and a rim on the flange engaging an end of the body and projecting substantially axially at the exterior of the body to directly seal against the outer wall of the body, and means securing the heads to the body, each of said means including a metal ring engaging outwardly against the flange of a head, and a flange on the ring bearing inwardly against the rim of the head flange and having a part turned under the edge portion of the rim to clamp outwardly against the same and to clamp against the body, said part being spaced from the adjacent end of the body to leave a portion of the rim in direct sealing contact with the outer surface of the body.

5. A container comprising a tubular body, a fibrous closure head for the body, a flange on the head bearing outwardly against the inner surface of the body, a rim on the flange projecting outwardly beyond the end of the body and then substantially axially at the outer surface of the body, a metal retaining ring engaging the flange of the head, a flange on the retaining ring bearing against the outer surface of the rim to clamp the same inwardly and a part on the flange of the ring turned about and confined to the edge portion of the rim to clamp outwardly against the inner surface of the rim.

6. In a container, a body, a fibrous head for the body having a flange engaging the inner wall of the body, a rim on the head flange extending outwardly over the end of the body and then substantially axially of the body at the outer surface of the body to directly seal against the inner surface, end, and outer surface of the body, a metal ring at the inner side of the head flange, a flange on the ring bearing against the outer surface of the rim to clamp the rim inwardly into sealing contact with the outer surface of the body, and a part on the flange of the ring wrapped under the edge portion of the rim and curled outwardly to clinch against its inner surface, the said part terminating in a plane below said end of the body.

7. In a container, a fibrous container body, a fibrous head for the body having a flange engaging the inner surface of the body, a rim on the head flange extending outwardly over an end of the body and then extending substantially axially of the body at the outer surface of the body to seal against the same, a metal ring within the flange of the head, a flange on the ring conforming to and bearing against the rim to urge the rim against the body, and a part on the flange of the ring curled about the edge portion of the rim to grip the same, to be partially embedded in the outer surface of the body and to distort the body to have sealing contact with the head flange and rim and to fully occupy the space between the head flange and rim, the said curled part being spaced from said end of the body.
